Patented May 5, 1914.

Application filed April 16, 1913. Serial No. 761,613. Term of patent 3½ years.

To all whom it may concern:

Be it known that I, ROBERT B. GRIFFIN, a citizen of the United States, and a resident of the borough of Manhattan, city and State of New York, have invented a new, original, and ornamental Design for a Wall-Covering, of which the following is a description.

The design is represented in the accompanying drawing.

As shown in the drawing, the design is illustrated in black and white. It is to be understood, however, that the background and the different configurations may be colored or tinted as desired.

The drawing is a plan view of a portion of a wall covering illustrating my new de-

sign, the dotted lines appearing thereon indicating the repeats of the design shown.

The design is especially adapted for use for the upper borders of wall paper or other wall covering.

I claim:

The ornamental design for wall covering as shown and described or any colorable imitation thereof.

In testimony that I claim the foregoing as my own, I have hereto affixed my signature in the presence of two witnesses.

ROBERT B. GRIFFIN.
